The ornamental design for a roll support, as shown and described.

DESCRIPTION

FIG. 1 is an isometric view of a roll support in accordance with the present invention;

FIG. 2 is a top plan view showing a portion of the roll support of FIG. 1, the bottom plan view being a mirror image thereof;

FIG. 3 is a side elevational view showing a portion of the roll support of FIG. 1;

FIG. 4 is a right end view showing the roll support of FIG. 1, the left end view being a mirror image thereof;

FIG. 5 is a cross-sectional view of the roll support of FIG. 1 taken along line 5—5; and,

FIG. 6 is a cross-sectional view of the roll support of FIG. 1 taken along line 6—6.

The roll support of FIG. 1 is shown with a portion cut away across its mid-section to indicate that it is of undetermined length, it being understood that the design repeats uniformly throughout its length.
